PACKAGE CARRIER HANDLE

William V. Buchanan and Richard D. Muir, New York,
N.Y., assignors to Command Mfg. Co., Inc., New York,
N.Y., a corporation of New York

Filed Nov. 18, 1963, Ser. No. 77,467

Term of patent 3½ years

(Cl. D87—2)

5—

5—

FIG. 1 is a front elevational view of the package carrier handle, showing our new design.

FIG. 2 is a top plan view thereof.

FIG. 3 is a bottom plan view thereof.

FIG. 4 is an end view thereof.

FIG. 5 is a sectional view as seen in the direction of the arrows along line 5—5 of FIG. 1.

We claim:

The ornamental design for a package carrier handle, substantially as shown.
